Primary Examiner — Susan E Krakower*Assistant Examiner* — L. A. Grabenstetter(74) Attorney, Agent, or Firm — Braxton, Hilton & Perrone, PLLC(57) CLAIM

The ornamental design for a tote bag with display pockets, as shown and described.

DESCRIPTION

FIG. 1 is a top, front perspective view of a tote bag with display pockets in accordance with the present invention; FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depicting handles, labels, zipper pulls, and interior surfaces represent unclaimed portions of the tote bag. The bold broken lines that appear on the surface of the tote bag represent unclaimed stitching. The woven and stippled textures are intended to be evenly distributed within the surfaces in which they appear.
